AIRPLANE

Alexander Kartveli, Huntington, N.Y., assignor to Republic Aviation Corporation, Farmingdale, N.Y., a corporation of Delaware

Filed Dec. 23, 1960, Ser. No. 63,323

Term of patent 14 years

(Cl. D71—1)

Des. 196,546

PAGE 2

FIG. 4

FIG. 5FIG. 6FIG. 1 is a top plan view of an airplane embodying the present design;

FIG. 2 is a rear elevation thereof;

FIG. 3 is a perspective view taken from the top rear thereof with the wings extended;

FIG. 4 is a view similar to FIG. 3 but with the wings retracted;

FIG. 5 is a perspective view taken from the bottom front thereof with the wings retracted; and

FIG. 6 is a perspective view taken from the bottom rear thereof with the wings retracted.

I claim:

The ornamental design for an airplane, substantially as shown,
